OPHTHALMIC MOUNTING

Carl E. H. Colliander, Providence, R. I., assignor
to Lorgnettes, Inc., Providence, R. I., a corpora-
tion of Rhode Island

Application June 4, 1932, Serial No. 615,380

8 Claims. (Cl. 88—42)

The present invention relates to ophthalmic mountings, more particularly mountings comprising a raised bridge, and its chief object is to provide a new and improved detachable connection between the bridge and the lens-holding members of mountings of this character, in order that the stock required to be kept on hand by the ordinary optician may be reduced to the minimum, and in order that any broken or unstylish part, whether lens rim or bridge, may readily be replaced by another.

The invention will be explained in connection with the accompanying drawing, in which Fig. 1 is a front elevation of an ophthalmic mounting constructed according to a preferred embodiment of the present invention; Fig. 2 is a horizontal section, upon a larger scale, taken upon the line 2—2 of Fig. 1, looking downward in the direction of the arrows; Fig. 3 is a similar, vertical section at one end of the bridge, the section being taken upon the line 3—3 of Fig. 2, looking in the direction of the arrows; Fig. 4 is a section, similar to Fig. 3, near the opposite end of the bridge, the section being upon a smaller scale than in Fig. 3, showing parts detached, the bridge being shown partly in elevation; Fig. 5 is a fragmentary view of a modification; Fig. 6 is a horizontal section taken upon the line 6—6 of Fig. 5, looking downward in the direction of the arrows, the parts being shown detached; and Fig. 7 is a similar view of a further modification.

The ophthalmic mounting of the present invention comprises, in its preferred embodiment, illustrated in Figs. 1 to 4, two substantially circular, metal, lens-holding rims 2 and 4, connected together by a metal bridge and having guards 38. The rims 2 and 4 are respectively provided with pockets 8 and 10, open at the top 12. In the illustrated embodiment of Figs. 1 to 4, the pockets 8 and 10 are closed at the bottom 14 and at the sides, as shown. The pockets 8 and 10 taper downward from the top 12 toward the bottom 14. The inner wall 5 of the pocket 8 is a continuation of the outer wall 7 of the rim 2, as shown in Fig. 4, and the inner wall 9 of the pocket 10 is similarly a continuation of the outer wall 11 of the rim 4, as shown in Fig. 3.

50 The ophthalmic mounting of the present invention is of the type that is supported upon the face by the guards 38, that rest upon the sides of the nose, in cooperation with temples 6. The bridge is therefore provided with an intermediate, raised portion 16, and two terminal or end

portions 18 and 20 depending from the raised portion 16. The lower extremities of the end portions 18 and 20 taper downward, as illustrated at 22 and 24, to correspond to the downward taper of the pockets 8 and 10. These lower extremities 22 and 24 are thus adapted to fit tightly in their corresponding pockets 8 and 10, with the end portions 18 and 20, and particularly their lower parts or extremities 22 and 24, conforming substantially to the shapes 10 of the respective rims 2 and 4. In the embodiment of the invention clearly illustrated in Figs. 1 and 3, the portions 18 and 20 contact throughout with respective outer surfaces 7 and 11 of the rims 2 and 4.

Each bridge end portion 18 and 20 is detachably held in place in its corresponding pocket 8 and 10 by a screw 26 that extends through an opening 28 in the outer wall of the pocket, through an opening 30 in the extremity 20 of the corresponding bridge end portions 18 and 20, and into an opening 32 in the inner wall of the corresponding pocket. To detach the bridge, all that is necessary is to remove the screw 26. The extremities 22 and 24 of the bridge may 25 then be freely moved upward, through the open tops 12 of the pockets 8 and 10, and the bridge replaced by another bridge of different shape, size or style.

The resulting bridge structure conforms in all respects to, and fits snugly against, the outer surfaces 7 and 11 of the rims, the end portions 18 and 20 of the bridge are detachable from the rims 2 and 4, and yet the parts are nevertheless securely held together in assembled relation.

According to the modification of Figs. 5 and 6, the pocket is of different nature, and consists of an open-sided recess 34 in a block 36 that is integrally secured, as by soldering, to the rim. 40 The bridge is provided with a projection 38 seated in its recess, and a flat part 40 that contacts with a flat part 42 of the block, and the parts are held together by a screw 44. The screw may extend either from the side, as illustrated in Figs. 5 and 6, or from any other direction, as the rear, illustrated in Fig. 7. Adjustments for pupillary distance may be effected in the portion 16 of the bridge, but if too drastic an adjustment is required, all that is necessary is 50 to replace the bridge by another. The optician is not, therefore, required to keep on hand more than a minimum number of bridges and rims, of different sizes, shapes and styles, as he is now enabled to assemble any style or size of 55

bridge, with any style or size of rim to produce a mounting suitable to the requirements of any patient. Similarly, if any part, whether lens rim or bridge, becomes broken or unstylish, it may 5 readily be replaced by another.

It will be understood that the invention may be further modified by persons skilled in the art, and such modifications are considered to be within the spirit and scope of the invention as 10 defined in the appended claims.

What is claimed is:

1. An ophthalmic mounting having, in combination, a bridge member having an intermediate raised portion and two end portions depending from the raised portion, the lower extremities of the end portions being tapering, two curved lens-holding rims each having a pocket, the inner wall of each pocket being a continuation of the curved outer wall of the corresponding lens-holding rim, the pockets being open at the top and being taperingly shaped to conform to the lower extremities of the respective end portions, whereby the said lower extremities fit tightly in their corresponding pockets, the end portions conforming substantially to the shapes of the rims throughout the major portions of their lengths, whereby the end portions contact with the rims throughout the said major portions of their lengths when the said lower extremities fit tightly in the pockets, and means detachably engaging the said lower extremities for detachably securing the said lower extremities in their respective pockets, the said lower extremities being freely movable into and out of their respective pockets through the open tops of the pockets when the detachable securing means are ineffective.

2. An ophthalmic mounting having, in combination, a bridge member having an intermediate raised portion and two end portions depending from the raised portion, the lower extremities of the end portions being tapering, two curved lens-holding rims each having a pocket, the inner wall of each pocket being a continuation of the curved outer wall of the corresponding lens-holding rim, the pockets being open at the top and being taperingly shaped to conform to the lower extremities of the respective end portions, whereby the said lower extremities fit tightly in their corresponding pockets, the end portions conforming substantially to the shapes of the rims throughout the major portions of their lengths, whereby the end portions contact with the rims throughout the said major portions of their lengths when the said lower extremities fit tightly in the pockets, and screws extending through two opposite walls of the pockets and through the said lower extremities for detachably securing the said lower extremities in their respective pockets, the said lower extremities being freely movable into and out of their respective pockets through the open tops of the pockets when the screws are removed.

3. An ophthalmic mounting having, in combination, a metal bridge member having an intermediate raised portion and two end portions depending from the raised portion, the lower extremities of the end portions being tapering, two substantially circular metal lens-holding rims each having a pocket open at the top, the pockets being correspondingly tapering, whereby the said lower extremities fit tightly in their corresponding pockets, the inner wall of each pocket being a continuation of the outer wall of the corresponding lens-holding rim, the end portions con-

forming substantially to the shapes of the rims throughout the major portions of their lengths, whereby the end portions contact with the rims throughout the said major portions of their lengths when the said lower extremities fit tightly 5 in the pockets, and screws extending through two opposite walls of the pockets and through the said lower extremities for detachably securing the said lower extremities in their respective pockets, the said lower extremities being freely movable into and out of their respective pockets through the open tops of the pockets when the screws are removed.

4. An ophthalmic mounting comprising two rims each having a tapering, open-topped pocket 15 the inner wall of which is a continuation of the outer surface of the corresponding rim, a bridge joining the rims together having an intermediate portion and two end portions depending from the intermediate portion, the end portions 20 conforming to and lying snugly against the outer surfaces of the rims throughout the major portions of their lengths, the lower extremities of the respective end portions being curved and tapered to correspond to the shape of the pockets, 25 whereby the said lower extremities fit tightly in the respective pockets, and means detachably engaging the said lower extremities for detachably securing the said lower extremities in the respective pockets, the said lower extremities being freely movable into and out of their respective pockets through the open tops of the pockets when the detachable securing means are ineffective.

5. An ophthalmic mounting having, in combination, a bridge member having an intermediate raised portion and two end portions depending from the raised portion, two lens-holding members each having a pocket open at the top, the inner wall of each pocket being a continuation of the outer wall of the corresponding lens-holding member, the end portions being shaped to conform to the shape of the lens-holding members throughout the major portions of their lengths and the lower extremities of the respective end portions being shaped to correspond to the shape of the pockets, whereby the said lower extremities fit tightly in their corresponding pockets and the end portions contact with the lens-holding members throughout 40 the said major portions of their lengths, and means detachably engaging the said lower extremities for detachably securing the said lower extremities in their respective pockets, the said lower extremities being freely movable into and 45 out of their respective pockets through the open tops of the pockets when the detachable engaging means are ineffective.

6. An ophthalmic mounting having, in combination, a bridge member having an intermediate raised portion and two end portions depending from the raised portion, two curved lens-holding members each having a tapering pocket open at the top, the inner wall of each pocket being a continuation of the outer curved 65 wall of the corresponding lens-holding member, the end portions being curved to conform to the curved shape of the lens-holding members throughout the major portions of their lengths and the lower extremities of the respective end portions being curved and tapered to correspond to the shape of the pockets, whereby the said lower extremities fit tightly in their corresponding pockets and the end portions contact with the lens-holding members throughout 70 the said major portions of their lengths, and means detachably engaging the said lower extremities for detachably securing the said lower extremities in their respective pockets, the said lower extremities being freely movable into and 75 out of their respective pockets through the open tops of the pockets when the detachable engaging means are ineffective.

5 said major portions of their lengths, and screws for detachably securing the said lower extremities in their respective pockets, the said lower extremities being freely movable into and out of their respective pockets through the open tops of the pockets when the screws are removed.

10 7. An ophthalmic mounting having, in combination, a bridge member having an intermediate raised portion and two end portions depending from the raised portion, two lens-holding members each having a pocket open at the top, the inner wall of each pocket being a continuation of the outer wall of the corresponding lens-holding member, the end portions being shaped to conform to the shape of the lens-holding members throughout considerable portions of their lengths and the lower extremities of the respective end portions being shaped to correspond to the shape of the pockets, whereby the said lower extremities fit tightly in their corresponding pockets and the end portions contact with the lens-holding members throughout the said considerable portions of their lengths, 15 and means detachably engaging the said lower extremities for detachably securing the said lower extremities in their respective pockets, the said lower extremities being freely movable into

and out of their respective pockets through the open tops of the pockets when the detachable engaging means are ineffective.

8. An ophthalmic mounting having, in combination, a bridge member having an intermediate 5 raised portion and two end portions depending from the raised portion, two curved lens-holding members each having a tapering pocket open at the top, the inner wall of each pocket being a continuation of the outer curved wall of the corresponding lens-holding member, the end portions being curved to conform to the curved shape of the lens-holding members throughout considerable portions of their lengths and the lower extremities of the respective end portions 10 being curved and tapered to correspond to the shape of the pockets, whereby the said lower extremities fit tightly in their corresponding pockets and the end portions contact with the lens-holding members throughout the said considerable portions of their lengths, and screws for detachably securing the said lower extremities in their respective pockets, the said lower extremities being freely movable into and out of their respective pockets through the open tops of the 15 pockets when the screws are removed.
